WILLIAM H. FRASSE, OF NEWARK, NEW JERSEY.

RESISTANCE COUPLING.

Application filed December 4, 1924. Serial No. 753,912.

My invention relates particularly to resistance-coupled circuits and, as herein embodied, is designed to produce, as a complete and self-contained unit, a resistance coupler, suitable and specially adapted for incorporation in radio amplifier or other circuits, to establish the necessary electrical relation between the successive electron-discharge tubes thereof.

The theory of resistance coupling is old and well-known in the art, but I find that considerable difficulty is experienced by the average worker in successfully and satisfactorily reducing the theory to practice and, as a result, the use of resistance coupled circuits has been greatly retarded. This is particularly noticeable in the radio art, where multi-stage tube amplifiers are now commonly employed in which, more from convenience than choice, transformer coupling is used between the stages, as transformers of various "makes" and wound in any ratio desired, are available in the market in the form of unit couplers.

The prevailing opinion being that resistance coupling is vastly superior to transformer coupling and that its general adoption would follow if made available in equally convenient form for incorporation in amplifier and other circuits, it is the object of the present invention to produce such a coupling, complete in unit form, ready for instant use and adaptable to different circuits by being provided with removable elements, interchangeable with others of different values.

The accompanying drawings will serve to illustrate a form suitable for carrying my invention into effect.

In the drawings—

Fig. 1 is a view in perspective of a resistance coupler unit, constructed in accordance with my invention;

Fig. 2 is a view in side elevation thereof;

Fig. 3 is a view in diagram of the unit circuit, and

Fig. 4 is a circuit diagram of a multi-stage resistance-coupled amplifier.

Referring to the drawings, 1 represents a base or block of any well known or suitable non-conducting material such as bakelite, hard rubber or the like.

The form and proportions of the base are unimportant but preferably it is cast as a

rectangular block, recessed on the underside to accommodate nuts or other fastening means 2, 2, etc., of four terminals indicated at 3, 4, 5 and 6, which are provided with clip-like extensions 3^a, 4^a, 5^a and 6^a, to receive resistance elements 7 and 8.

As shown, the resistance element 7 is clipped between the terminals 3 and 4 and the resistance element 8 is similarly clipped between the terminals 5 and 6.

Additional extensions 9, 9, from the terminals 3 and 5, are provided with clips 10, 10, to receive a condenser 11, as shown.

Considering the coupler unit, as above described, without reference to the amplifier circuits in which it is designed to be incorporated, the resistance elements and interposed condenser are connected in series, through the four terminals of the base, as shown in Fig. 3 and in this relation are adapted to be directly connected between the tubes of any two amplifier stages, as indicated, for example, in diagram in Fig. 4.

As shown in this figure, the terminals 3, and 4 are connected respectively to the plate and grid of the tubes of the two amplifier stages to be coupled. These connections having been made, the coupling is completed by connecting the terminal 5 to the positive side of the B-battery and the terminal 6, to the filament lead.

From the foregoing it will be seen that the coupling of two tube amplifier stages involves only the connecting of the four leads, above indicated, to the terminals of the coupler unit and as these terminals are clearly marked, no confusion, uncertainty or doubt can arise in the mind of the user as to the proper connections.

In adapting the coupler to different circuits or tubes, the user, aided by a suitable chart or table, ascertains the necessary values for the resistance elements and the condenser and secures them in position by pressing them into the clip-terminals of the base.

As the many important advantages of the invention will be apparent, from the foregoing description, it will be unnecessary to list and elaborate upon them.

Having thus described my invention, what I claim is:

1. A resistance coupling unit for tube amplifier circuits, comprising a suitable base providing a plurality of definitely spaced

terminals, and two resistance elements and an interposed condenser connected in series through the terminals, said resistance elements and condenser being removably held in clip-like extensions of the terminals.

2. A resistance coupling unit for tube amplifier circuits, comprising a suitable base providing four definitely spaced terminals each having a clip-like extension, and two resistance elements and an interposed condenser connected in series through the four

terminals by being removably held in the clips thereof.

3. A resistance coupling unit for tube amplifier circuits, comprising a suitable base 15 providing four terminals having clip extensions, and two resistance elements and an interposed condenser connected in series through the four terminals by being held in the clips and separately removable therefrom. 20

WILLIAM H. FRASSE.
